UNITED STATES PATENT OFFICE.

GLENN E. NORMAN, OF NEVADA, MISSOURI.

TUNNEL-KILN.

1,872,773.

Specification of Letters Patent. Patented Mar. 28, 1932.

Application filed February 17, 1930. Serial No. 358,366.

To all whom it may concern:

Be it known that I, GLENN E. NORMAN, a citizen of the United States, residing at Nevada, in the county of Vernon and State 5 of Missouri, have invented certain new and useful Improvements in Tunnel-Kilns, of which the following is a specification, reference being had therein to the accompanying drawing.

10 This invention relates to improvements in tunnel kilns, one object of the invention being the provision of a kiln wherein all of the heating units are utilized to the greatest maximum, the exterior of the walls of the 15 same being provided with longitudinal air channels open at one end to the air and the opposite end to a collecting chamber from whence it is led, through the instrumentality of the fan or any other means, to a drier 20 where the air acts previously upon the material to be baked before the same is permitted to enter the kiln.

A still further object of this invention is the provision of a tunnel kiln in which the 25 outer wall is composed of hollow tile laid with the air passages thereof longitudinally of the kiln so that air may be heated while in transit by the combustion chamber of the kiln and be carried away from the kiln by 30 means of an exhaust fan for drying the green clay ware, thus, in a practical way reclaiming the greatest part of the waste heat from the combustion chambers and also from the 35 cooling ware as it travels away from the combustion chambers, the construction being so that the ware is particularly heated as it enters the kiln and also further constructed that the greatest part of the heat is radiated through the top and sides of the kiln 40 where it effects the longitudinal air passages.

A still further object of this invention is the provision of cool air supplying pipes located adjacent the floor of the kiln with 45 adjustable means for controlling the supply of air thereto so that the heat from above is prevented from going down to heat the iron decks of the car below the ware, the said decks having been covered with fire 50 brick before placing the ware thereon to be treated.

In the accompanying drawings:

Figures 1 and 1^a represent horizontal cross sectional views of the complete tunnel kiln, 55 the portion shown in Fig. 1^a being adapted

to be connected at the right to that shown in Fig. 1.

Fig. 2 is a section taken on line 2—2 of Fig. 1.

Fig. 3 is section taken on line 3—3 of Fig. 1.

Fig. 4 is a section taken on line 4—4 of Fig. 1.

Fig. 5 is a section taken on line 5—5 of Fig. 1.

Fig. 6 is an enlarged longitudinal sectional view of the kiln adjacent the hood.

Referring to the drawings, the numeral 10 designates the entrance half of the kiln and 11 the exit half thereof. Adapted to 70 surround the outer surface of the kiln throughout the length thereof, is the hollow tile work 12, the openings 13 of which are all disposed in longitudinal alignment according to the layers of the tile throughout 75 the complete length of the kiln, they being open to the air at 14 so that the air passing therethrough is heated gradually from the entrance end thereof and is delivered through the tile both upon the sides and 80 dome of the kiln, as clearly shown in Fig. 2, at 15, 16 and 17, to where it finally enters the air receiving casing 18 at the opposite end of the kiln, an air duct 19 being led away from same so that the air may be exhausted after being heated by the heat from 85 the dome and walls of the kiln before being delivered to driers, not shown, for the green clay wares.

As shown in Fig. 5, all of the wall tiles, 80, 15, 16, and 17, open into the chamber 18 and as the exhaust fan, not shown, draws the air from such chamber it also draws it from the full length of the tunnel kiln 90 where it enters at the opening 14.

The inside of the kiln, opposite the enlarged section 22 thereof, is lined with shale brick 20, while that adjacent the heating portion thereof is lined with fire brick 21. At the enlarged portion 22 of the kiln there is provided by means of the checker or open brick work 23, the two oppositely disposed chambers 24 and 25, which are the combustion chambers and to which are led the burners 26 and 27.

Mounted in the base of the kiln throughout the length thereof, are the rails 28 which form the track for the car 29 which is provided with the iron platform 30 covered with fire brick 31 by which the decks are 110

protected to some extent and which also provide a support for the tile or brick ware 32 that is to be acted upon.

It will also be noted that there is provided throughout the length of the kiln at opposite points of the walls thereof, the opposite recesses or channels 33 in which the sides of the car platform are adapted to fit in and thus to a great extent, confine the cool air below the platform of the car, this cool air being directed forwardly in opposition to the hot air, by means of the apertured pipes 34 disposed longitudinally through a greater portion of the heating chamber of the kiln on opposite sides of the track, these pipes being supplied with air by means of the blower 35 located at one end of the kiln and the amount of air permitted to be ejected therefrom being regulated by means of the valve 36 at the opposite ends of the pipes and accessible at the outside of the kiln. By this means it will be seen that currents of cool air are forced in opposition to the hot air and the walls and platform of the car, the platform being further protected by the fire brick 31 which thus maintains at a temperature which is not injurious to the car and platform during the treatment of the tile or brick in transit through the kiln.

In order to assist in regulating the heat within the kiln and thus the temperature at which the ware is first subjected when entering the kiln, at the extreme left in Fig. 1, there are provided in the lateral wing 37 thereof, the chambers 38, one at each side and adapted to form communicating means between these chambers and the tunnel of the kiln are a plurality of openings 39, each one of which is controlled by the manually operated damper 40 from the exterior of the kiln.

From the foregoing description, taken in connection with the drawings, the operation of the present kiln will be readily understood, but briefly stated it is as follows: The car carrying the dry ware to be treated enters at the extreme left in Fig. 1, and is there subjected to warm air which is drawn through the tunnel from right to left, and consequently, has been preheated opposite the combustion chambers, and being lighter than the air in the lower portion will act more thoroughly upon the material upon the car. As the car approaches the combustion chamber portion the material thereon is subjected to the baking heat, the car being protected at this time by means of the cool air from the apertured pipe 34 and is then passed on to the cooling end and finally out of the kiln, the operation being timed so that the brick or tile is properly baked during this movement from one end to the other.

The heat exerted upon the walls of the kiln, as heretofore described, acts upon the surrounding tile so that the air drawn there-

through and finally entering the exhaust drum or casing 18 is properly heated, the air from internally of the kiln also being brought through the damper controlled openings 39 into the chambers 38 and finally 70 into the exhaust chambers 18, thus supplying additional dry air for drying the green material and thus utilizing to the greatest maximum the heat of the kiln, which in other kilns is a waste product.

75

What I claim as new is:

1. A tunnel kiln comprising a longitudinal structure, the walls and dome of which are provided with longitudinal air passages the full length thereof adapted to be heated 80 by the heat affecting the walls of said structure, and an exhaust air directing compartment at one end of the structure into which all of the longitudinal air passages enter.

2. A tunnel kiln including a structure 85 having an entrance end, the walls of which are heated by air drawn from the opposite end, an intermediate heating and combustion portion having a cooling and outlet end, all arranged in longitudinal and connected relation, one with the other.

3. A tunnel kiln including a structure having an entrance end, an intermediate heating and combustion portion having a cooling and outlet end, all arranged in longitudinal and connected relation, one with the other, the said walls and dome of said structure being surrounded with a hollow casing 95 open to the atmosphere at the outlet end of the kiln, and an air receiving and directing chamber at the inlet end of the kiln for receiving the air from the hollow casing.

4. A tunnel kiln including a structure having an entrance end the walls of which are heated, an intermediate heating and 105 combustion portion having a cooling and outlet end, all arranged in longitudinal and connected relation, one with the other, and independent cooling means disposed at the base of the structure the full length of the 110 combustion chamber and extended beyond the entrance and exit end thereof.

5. A tunnel kiln including a structure having an entrance end, the walls of which are heated, an intermediate heating and 115 combustion portion having a cooling and outlet end, all arranged in longitudinal and connected relation, one with the other, independent cooling means disposed at the base of the structure the full length of the 120 combustion chamber and extended beyond the entrance and exit end thereof, and adjustable means for controlling the supply of air thereto.

6. A tunnel kiln including a structure having an entrance end, an intermediate heating and combustion portion having a cooling and outlet end, all arranged in longitudinal and connected relation, one with the other, the walls and dome of said structure 125

130

- being surrounded with a hollow casing open to the atmosphere at the outlet end of the kiln, an air receiving and directing chamber at the inlet end of the kiln for receiving the air from the hollow casing, and cooling means disposed at the base of the structure adjacent the combustion chamber and for a distance beyond the entrance and exit end thereof.
- 10 7. A tunnel kiln including a structure having an entrance end, an intermediate heating and combustion portion having a cooling and outlet end, all arranged in longitudinal and connected relation, one with the other, the walls and dome of said structure being surrounded with a hollow casing open to the atmosphere at the outlet end of the kiln, an air receiving and directing chamber at the inlet end of the kiln for re-
- ceiving the air from the hollow casing, and adjustable means for controlling the supply of air thereto.
8. A tunnel kiln comprising a longitudinal structure, the walls and dome of which are provided with longitudinal air passage the full length thereof, open at the exit end of the structure, the intermediate portion of the structure being the combustion chamber whereby the air passing from the exit toward the entrance end is heated in the walls and dome thereof, and a surrounding casing at the entrance end into which the longitudinal air passages enter for receiving the heated air.
- In testimony whereof I affix my signature.

GLENN E. NORMAN.
